PET SLEEPING BAG

Joseph B. Mashburn, 801 E. Yosemite Ave.,
Madera, Calif. 93637

Filed Mar. 10, 1971, Ser. No. 123,131

Term of patent 7 years

Int. Cl. D30—02, 06

U.S. Cl. D30—1

FIG. 1.

FIG. 2.

FIG. 3.

FIG. 4.

FIG. 5.

FIG. 6.

FIG. 1 is a top plan view of a pet sleeping bag, showing my new design;

FIG. 2 is a front elevational view;

FIG. 3 is a side elevational view, the opposite side being substantially a mirror image thereof;

FIG. 4 is a rear elevational view;

FIG. 5 is a bottom plan view; and

FIG. 6 is a front, top and right side perspective view thereof.

The broken lines indicate stitching.

I claim:

The ornamental design for a pet sleeping bag, as shown and described.
